TOILET PAPER ROLL CABINET

Roy W. Johnson, Rockford, Ill.

Application January 2, 1940, Serial No. 311,970

12 Claims. (Cl. 242—55.5)

This invention relates to improvements in toilet paper roll cabinets.

The principal object of my invention is to provide an attractive one-piece molded plastic cabinet of the kind mentioned so designed that simple and inexpensive molds may be used and the cabinet may be produced in quantity at a reasonably low cost.

A further object of the invention is to provide a cabinet designed to effectively conceal the toilet paper roll while still making the paper easily accessible for use, the cabinet being further designed for quick and easy removal from a small supporting spring clip on the wall for re-loading purposes, and designed so that removal of the previous roll's spool and entry of a new roll and remounting of the refilled cabinet on the spring clip can be attended to easily by any mechanically unskilled person.

These and other objects of the invention are brought out in the course of the following detailed description in which reference is made to the accompanying drawing, wherein—

Fig. 1 is a cross-section of a roll cabinet made and mounted in accordance with my invention;

Fig. 2 is a perspective view of the molded one-piece roll cabinet removed from its spring clip on the wall;

Fig. 3 is a perspective view of the spring clip attached to the wall;

Fig. 4 is a longitudinal sectional detail on the line 4—4 of Fig. 1, with an intermediate portion of the section broken away to conserve space in the drawing and show the parts on a large scale, and

Fig. 5 is a rear elevation of the upper portion of the roll cabinet showing the integral hollow lugs used for mounting the cabinet on the clip.

The same reference numerals are applied to corresponding parts throughout the views.

The roll containing cabinet 6 of my invention is of a one-piece molded plastic construction comprising a generally semi-cylindrical main peripheral wall 7, and sides 8 and 9 integral therewith. A reinforcing rib 10 and a paper tearing edge 11 are provided at opposite ends of the main wall 7. If desired, ornamental beads 1a may be molded on the outside of the cabinet wall 7, as shown. The cabinet 6, as will soon appear, is designed to be molded of a suitable plastic material in a simple non-collapsible mold for purposes of lower mold costs and generally better economy and speed in manufacture.

The usual cardboard spool 12 of a standard size toilet paper roll 13 is arranged to be mounted

snugly on a wooden roller 14 which is provided in connection with this cabinet. Supports for the rotation of the roller 14 are provided at one end by a pin 15 equipped with a locating flange 15a and, at the other end, by a spring-pressed "bullet" detent 16. The projecting heads of this pin 15 and spring detent 16 are constructed to slide in grooves 17 and 18 molded in the cabinet side walls 8 and 9 and enter bearings 19, and 20, respectively, formed suitably by holes in said walls. The entire back of the cabinet is open, as indicated at 1b, and substantially the entire bottom likewise, as indicated at 1c, so that a standard sized roll of toilet paper can be entered easily, especially when arranged to be guided by the grooves 17 and 18 which extend in a plane bisecting the angle defined between the open back and bottom of the cabinet, as shown in Fig. 1. The roller 14 is maintained in operating position through the pressure exerted by spring 21 which holds the heads of pin 15 and detent 16 within their respective bearing holes. The spring pressure just mentioned also serves to provide a frictional drag to resist too free rotation of the roller 14 whereby to avoid dispensing paper from the roll 13 beyond the desired length, while still permitting the paper to be withdrawn easily.

To remove the roller 14 from the cabinet 6 when the roll 13 is used up, it is necessary only to expel the head of the detent 16 from its bearing hole 20 and into the groove 18, whereupon the pin 15 can be withdrawn from its hole 19 by endwise movement of the roller and, with both pin and detent in the grooves 17 and 18, the spool and roller can be slid out of the cabinet. A pin 22, which is supplied with the cabinet, as hereinafter appears, may be inserted in hole 20 and pressed against the detent 16 to force the latter into the groove 18.

The cabinet is designed for attachment to a wall 23 in the desired place by mounting the same on a spring clip 24 of V-shaped cross-section which is secured to the wall by screws 25 and 26. The inside surfaces of a pair of hollow V-shaped lugs 27 and 28 which are molded integrally with the cabinet inside its two upper corners fit in the clip so as to depress the free arm 29 of the clip 24 while the upper edge 30 of the container is sprung beneath the forwardly curled upper edge 31 of the attaching arm 31a, the arms 29, 31a being only slightly shorter in length than the inside width of the cabinet so that the arms will engage the inner sides of the side walls 8, 9 to prevent sidewise displacement of the cabinet relative to the clip. With this method of attach-

ment, the cabinet is securely attached to the wall but may be readily removed therefrom by gripping the cabinet and first applying a relatively slight downward pressure so that the free arm 5 29 of the clip 24 will move in a like direction and release the edge 30 from the retaining projection 31. It will be noticed in Fig. 1 that the lugs 27, 28 when engaged in the spring clip do not quite reach the crotch 24a thereof, so that the release 10 movement described is permitted. It will also be noticed that the lugs 27, 28 have their inner walls 27a, 28a inclined in a plane substantially parallel with the grooves 17, 18 to facilitate molding. The curled edge portion 31 provides a convenient holder for the pin 22 previously mentioned, the head of the pin neatly covering up the end of this hollow portion when the shank of the pin is entered therein, as indicated in Fig. 3. The closure 22a for the other end may be fixed or 15 20 movable and of like form to pin 22.

A spring tongue 32 attached to the clip 24 by any suitable method, as by welding, provides an additional frictional drag on the turning of the roll 13 by exerting a light pressure against the roll 13, whereby to prevent its spinning.

As has been mentioned, the molding of this cabinet requires only a simple non-collapsible type mold. Thus, the main wall 7, which is concentric except at the mounting end with the 30 bearing holes 19, 20 for the roller, includes not more than 180 degrees, measured 90° both ways from the plane of the grooves 17, 18, as indicated by the dot-and-dash line a—b in Fig. 1. For a like reason, grooves 17, 18 and the inner 35 walls of the hollow lugs 27, 28, all of which are in parallel relation, are made at right angles to said plane a—b. By virtue of this design, the simple non-collapsible type ram of the plastic molding machine is easily removable from the 40 cabinet after the molding thereof. While any suitable plastic material of the Bakelite type may be used in the production of the present cabinet, I at present prefer what is known as "Beetle."

45 The foregoing description conveys a good understanding of the objects and advantages of my invention. The appended claims have been drawn with a view to covering all legitimate modifications and adaptations.

50 I claim:

1. A paper roll cabinet comprising a hollow cabinet body formed to provide spaced parallel side walls and a transverse wall connecting the edge portions of the side walls only over the top 55 and front portions of the cabinet body, whereby to leave substantially the entire back and bottom of said body open to admit a roll of paper, said side walls having their rear wall-engaging edges in a plane substantially at right angles to the top wall of the cabinet body, and said top wall having one or more downwardly extending projections by means of which said cabinet is adapted to be supported on a wall, and the side walls of said cabinet having grooves provided in the 60 inner sides thereof extending upwardly and forwardly from points adjacent the rear portion of the bottom edges of said side walls, and said grooves terminating at their upper ends in coaxially aligned bearings at the approximate centers of said side walls adapted to support the projecting coaxially aligned pivots for a roll of paper.

65 2. A cabinet as set forth in claim 1, wherein said downwardly extending projections on the top wall are inclined in a plane substantially

parallel with said grooves, the cabinet body being molded in one piece with said projections integral therewith.

3. A cabinet as set forth in claim 1, wherein said downwardly extending projections on the top wall are inclined in a plane substantially parallel with said grooves, the cabinet body being molded in one piece with said projections integral therewith, and the lower edge of the transverse wall lying approximately in a transverse plane 10 normal to the side walls of the cabinet body and also normal to the grooves and projections.

4. A cabinet as set forth in claim 1, wherein said downwardly extending projections on the top wall are inclined in a plane substantially parallel with said grooves, the cabinet body being molded in one piece with said projections integral therewith, and the lower edge of the transverse wall lying approximately in a transverse plane 15 normal to the side walls of the cabinet body and also normal to the grooves and projections, the lower edge portion of said transverse wall being tapered so as to provide a sharp edge over which the paper from the roll is adapted to be fed, whereby to facilitate tearing off the dispensed 20 portion.

5. A paper roll cabinet of the character described, comprising a hollow cabinet body formed to provide side walls and a connecting transverse wall to enclose a roller of paper, the side walls having grooves provided on the inner sides thereof extending in parallel relation to one another from the outer edges of the side walls and terminating at their inner ends in coaxially aligned 30 bearings adapted to receive the projecting coaxially aligned pivots on the ends of a roll of paper, one of the bearings being formed by an opening through the side wall of the cabinet body, a roll supporting roller having coaxially aligned pivots projecting from the opposite ends 35 thereof for reception in the aforesaid bearings and adapted to be guided toward said bearings by sliding movement in the grooves, one of said projecting pivots on the roller having a spring 40 for moving the same endwise and normally holding the same extended, whereby the same is adapted to move under spring pressure into engagement in the bearing opening, and a pin demountably supported with the cabinet on a wall and adapted to be entered in said bearing 45 opening from the outside of the cabinet to displace the spring pressed pivot from the bearing opening into the groove to permit removal of the roller from the cabinet.

6. As an article of manufacture, a one-piece 50 molded cabinet body for a paper roll cabinet comprising spaced parallel side walls and an integral transverse connecting wall closing only the top and front of the cabinet and leaving substantially the entire back and bottom of the cabinet open, the rear edges of the side walls being in coplanar relation and approximately at right angles to the plane of the top wall of the cabinet body for engagement with a supporting wall in a room, said top wall having one or more 55 downwardly extending projections at the rear thereof by means of which said cabinet is adapted to be demountably secured to the wall, and the side walls of said cabinet body having parallel grooves provided therein extending from 60 points adjacent the rear of the bottom edges upwardly and forwardly and terminating in coaxially aligned bearings at the approximate centers of the side walls adapted to receive projecting 65 coaxially aligned pivots on a roll of paper.

7. An article of manufacture as set forth in claim 6, wherein the downwardly extending projections on the top wall have their inner surfaces in a plane substantially parallel with the grooves in the side walls. 5
8. An article of manufacture as set forth in claim 6, wherein the downwardly extending projections on the top wall have their inner surfaces in a plane substantially parallel with the grooves in the side walls, the transverse wall connecting said side walls terminating at its lower end approximately in a plane normal to the inside surfaces of said projections and said grooves. 10
9. An article of manufacture as set forth in claim 6, wherein the downwardly extending projections on the top wall have their inner surfaces in a plane substantially parallel with the grooves in the side walls, the transverse wall connecting said side walls terminating at its lower end approximately in a plane normal to the inside surfaces of said projections and said grooves. 15
10. A paper roll cabinet comprising a hollow cabinet body formed to provide spaced parallel side walls and a transverse wall connecting the edge portions of the side walls only over the top and front portions of the cabinet body, whereby to leave substantially the entire back and bottom of said body open to admit a roll of paper, said side walls having their rear wall engaging edges in a plane substantially at right angles to the top wall of the cabinet body, and said top wall having one or more downwardly tapering projections on the inner side thereof adjacent its rear edge, a spring clip of V-shaped cross- 20
- section whereby one arm of the V provides an attaching portion for engagement with the wall of a room and the other arm of the V provides a springable portion adapted to be engaged and depressed by the aforesaid tapered projections on the top wall of said cabinet body for support of the cabinet body on the wall, said clip having a forward projection on the upper end of the wall engaging arm thereof arranged to engage on top of said cabinet body to retain the same detachably in the clip, said clip serving by engagement with the inner sides of the side walls of the cabinet body to prevent lateral displacement of said cabinet body relative to said clip. 25
11. A device as set forth in claim 10, including a roll engaging spring tongue depending from the spring clip intermediate the ends thereof and projecting forwardly from the wall for engagement with a paper roll in the cabinet, frictionally to resist turning of the roll. 30
12. A device as set forth in claim 10, wherein the forwardly reaching projection on the clip is formed by a curled edge portion forming a hollow cylindrical projection open at its opposite ends, the device including closures for the opposite ends of said hollow cylindrical projection, at least one of said closures comprising a pin removably entered in the end of the hollow cylindrical projection to form a closure therefor, said pin having a shank portion small enough in diameter to be entered through a hole in the side wall of the cabinet body in coaxial alignment with the central bearing provided therein for the paper roll pivot, substantially as and for the purpose described. 35

ROY W. JOHNSON.
